LADY'S STOCKING

George J. Apar, Long Island City, N. Y., assignor of one-half to Bambach & Roth Hosiery Mills, Philadelphia, Pa., a partnership, and one-half to Colleen Hosiery Co., New York, N. Y., a partnership

Application September 11, 1952, Serial No. 21,428
Term of patent 3½ years

(Cl. D47—7)

To all whom it may concern:

Be it known that I, George J. Apar, a citizen of the United States of America and a resident of Long Island City, county of Queens, State of New York, have invented a new, original, and ornamental Design for a Lady's Stocking, of which the following is a specification, reference being had to the accompanying drawing, forming a part hereof, in which:

Fig. 1 is a side view of a stocking made in accordance with my design.

Fig. 2 is a fragmentary back view of said stocking.

I claim:

The ornamental design for a lady's stocking, substantially as shown.

GEORGE J. APAR.
